UNITED STATES PATENT OFFICE.

ERSKINE F. BICKFORD, OF MALDEN, MASSACHUSETTS.

DESIGN FOR RUBBER OVERSHOE.

Specification forming part of Design No. 7,634, dated August 18, 1874; application filed May 13, 1874.
[Term of Patent 7 years.]

To all whom it may concern:

Be it known that I, ERSKINE F. BICKFORD, of Malden, of the county of Middlesex and State of Massachusetts, have invented a new and useful and ornamental Design for an India-Rubber Overshoe; and do hereby declare the same to be fully represented in the accompanying drawings, of which—

Figure 1 is a top view, and Fig. 2 a side elevation, of a shoe with such design.

The design relates especially to the upper; and consists, first, in forming such along on its upper edge to represent in bas-relief a corded binding, A; second, in forming the lower part of the upper, or that contiguous to the sole to exhibit a foxing, B, terminating at the heel against the corded binding, and from

thence around the shoe in corded edge a, as shown. The space C between the foxing and the binding is to be ornamented in bas-relief to represent the “pebbling” or broken surface of what is termed pebbled leather, the whole being as represented.

I claim—

The ornamental design, substantially as described and represented, for the upper of an india-rubber overshoe, such embracing the foxing and binding with the pebbling in relief, all arranged and formed as shown.

ERSKINE F. BICKFORD.
